ADJUSTABLE GUNSTOCK

Earnest N. Baker, Kansas City, Mo., assignor to
Fred D. Baker, Buckner, Mo.

Application September 29, 1952, Serial No. 312,115

3 Claims. (Cl. 42—73)

This invention relates to improvements in firearms and particularly with respect to novel structure for adjustably securing the gunstock to the receiver, the primary object being to include means for permitting lateral adjustment of the stock relative to the receiver, as well as elevational adjustments of such gunstock.

An important object of this invention is to provide an adjustable gunstock having structure capable of permitting minute changes in the relative positions of the stock and the receiver in the field without the need of tools or other accessory items.

Another object hereof is to provide a gun having a ball and socket joint interconnecting the receiver of the gun and the stock thereof so formed as to assure strength and rigidity irrespective of the selected position of the interconnected parts.

Another object hereof is to provide a gunstock having adjusting characteristics such as to render the stock universally adaptable for attachment to the receiver of various types of guns.

Another object hereof is to provide clamping structure for holding the stock in adjusted positions that is entirely housed within the stock and which projects therefrom automatically simply by removing a small fastener.

Other objects include the way in which a tapered shim is utilized to determine the relative positions of the receiver and the gunstock in a lateral direction; the manner of providing extensible elements on the clamping structure for facilitating tightening and loosening by hand; and other objects including details of construction, all of which will be made clear or become apparent as the following specification progresses.

In the drawings:

Figure 1 is a fragmentary, side elevational view of a gun provided with an adjustable stock made pursuant to the present invention, parts being broken away and in section for clearness.

Fig. 2 is a longitudinal, cross-sectional view through the gunstock taken on line II—II of Fig. 1.

Fig. 3 is an elevational view similar to Fig. 1 parts being broken away for clearness illustrating the shiftable structure in the extended position.

Fig. 4 is a fragmentary, detailed, enlarged, cross-sectional view taken on line IV—IV of Fig. 3; and

Fig. 5 is a fragmentary, perspective view of the shiftable structure removed from the gunstock and devoid of the spring actuator.

As above indicated, it is contemplated by the present invention that gunstock 10 be adjustably mounted on receiver 12 and, to this end there is provided an adaptor block 14 on one end of the receiver 12 provided with a convex socket 16 complementary with concave end 18 of the stock 10. Centrally perforated block 14 receives a post 20 that also passes through a perforated, tapered shim 22 interposed between the block 14 and the receiver 12. Post 20 has a polygonal plate 24 on the innermost end thereof fitted within a groove 26 formed in the receiver 12. The elongated stock 10 has a longitudinal

2

bore 28 therethrough having an enlarged portion 30 at one end thereof and a frusto-conical portion 32 at the opposite end thereof.

An out-turned, annular flange 34, on a screw 36 within the bore 28, bears against a shoulder 38 that faces toward the butt end of the stock 10. The post 20 extends into the bore portion 30 and receives a hinge member 40 having an internally tapped opening 42 at one end thereof for receiving the screw 36. The opposite end of the hinge member 40 is bifurcated to receive flattened portion 44 of post 20 and a hinge pin 46 disposed transversely of the stock 10 concentric with the socket 16 and the end 18, interconnects hinge member 40 and post 20. That end 48 of the screw member 36 extending beyond the flange 34, is polygonal in cross-section for slidably, but non-rotatably receiving an elongated slide member 50 provided with a pair of opposed, longitudinal slots 52.

A cross-pin 54 on the polygonal portion 48 extends into the slots 52 for sliding movement therein. A spring 56 coiled about the slide member 50 and the end portion 48 is interposed between flange 34 and a flange 58 on the slide member 50 intermediate the ends of the latter. A cylindrical portion 60 on the outermost free end of the slide member 50 has an annular groove 62 and a pair of opposed slots 64 for swingably receiving handle member 66 by means of pivot pins 68.

A small spring clip 70 in the stock 10, normally extends into the groove 62 to hold the slide member 50 in the position shown by Figs. 1 and 2 of the drawings, and a plug 72 closes the base end of the bore 28.

When the slide member 50 is in the position shown by Fig. 3 of the drawings, the opposed handle members 66 may be swung outwardly on their pivot pins 68, thereby presenting a hand-grip for facilitating turning of the screw member 36. When the latter is turned in one direction to loosen the same, gunstock 10 may be raised or lowered with respect to the receiver 12 as desired as the concave end 18 thereof slides within the convex socket 16. Also, when the clamping means is thus loosened, the tapered shim 22 may be rotated with respect to the post 20 so that the gunstock may be shifted laterally for "cast on" or "cast off" purposes. Thereupon, the gunman may manipulate the handle 66 to tighten the screw member 36 in the hinge 40 to tightly clamp the shim 22 between the adaptor block 14 and the receiver 12 and to also tightly clamp the end 18 of the gunstock 10 tightly within the convex socket 16.

During the swinging movement of the gunstock 10 with respect to the adaptor block 14, the hinge 40 swings on the pivot pin 46 with respect to the post 20. During lateral adjustment, the gunstock 10 and the adaptor block 14, shift with respect to the receiver 12 there being sufficient looseness of fit to permit such relative movement. After the gun has been so adjusted, the handles 66 are swung on their pivot 68 to the positions shown in Figs. 1, 2 and 3, and the slide element 50 is forced into the bore portion 30 against the action of spring 56 until the annular groove 62 is aligned for receiving the spring clip 70. Thereupon, plug 72 is reinserted within the bore portion 30.

Clip 70 is especially chosen for easy removal with a pocketknife or other sharp instrument thereby requiring no tools in the field to permit quick and simple adjustments in the manner aforementioned. When the clip 70 is removed, spring 56 automatically projects the slide 50 from the bore portion 30 where the handles 66 are readily accessible.

Having thus described the invention what is claimed as new and desired to be secured by Letters Patent is:

1. In a gun, a receiver; a post secured to the receiver and extending outwardly beyond one end thereof; an adaptor block mounted on the post at said one end of

the receiver, said block being provided with a convex socket; a stock provided with a bore and a concave end fitted in said socket for swinging movement of the stock relative to the block; a transverse pivot pin mounted on said post within the bore concentric to said socket and to said concave end; a hinge mounted on the pivot pin within the bore; a screw in the bore and connected with the hinge for swinging movement with the stock and with respect to the post; and an abutment element on the screw bearing against the stock within the bore for holding the block clamped between the receiver and the stock, there being a screw actuating member slidably mounted on the screw for movement into and out of the bore toward and away from said abutment element at that end of the bore opposite to the socket.

2. In a gun as set forth in claim 1 wherein is provided resilient means within the bore and bearing against said member for yieldably biasing the latter toward the outermost end of its path of travel, and releasable means for holding the member within the socket.

3. In a gun as set forth in claim 1 wherein said actuating member is provided with a laterally extending handle swingably secured thereto for movement to a collapsed position when the member and the handle are retracted into the bore.
